GAME BOARD

Lee McCartney, Havre, Mont. 59501

Filed Mar. 23, 1973, Ser. No. 344,433

Term of patent 14 years

Int. Cl. D21—01

U.S. Cl. D34—5 SS

FIG. 1.

FIG. 2.

FIG. 1 is a plan view of the game board showing my new design;

FIG. 2 is an enlarged broken away detail of the upper right hand corner of the game board shown in FIG. 1. The board is of conventional thickness.

I claim:

The ornamental design for a game board, as shown and described.
